Primary Examiner — W. A. Teddy Falloway*Assistant Examiner* — Yuan YuanCLAIM

The ornamental design for a sports net as shown and described.

DESCRIPTION

FIG. 1 is a perspective view of a sports net showing the claimed design;

FIG. 2 is a front-side elevation view thereof;

FIG. 3 is a back-side elevation view thereof;

FIG. 4 is a right-side elevation view thereof, the left-side elevation view being a mirror image thereof;

FIG. 5 is a top plan view thereof; and,

FIG. 6 is a bottom view thereof.

Broken lines in the figures show portions of the sports net that form no part of the claimed design.
